[57] CLAIM

The ornamental design for a cut for a gem, as shown and described.

DESCRIPTION

FIG. 1 is a top perspective view of a cut for a gem showing my new design;

FIG. 2 is a bottom perspective view of my design.

FIG. 3 is an end elevational view of my design.

FIG. 4 is an end elevational view of my design from the end opposite to the end shown in FIG. 3.

FIG. 5 is a side elevational view of my design (the opposite side elevational view, not shown, being symmetrical).

FIG. 6 is a top plan view of my design; and,

FIG. 7 is a bottom plan view of my design.
